CAR CONSTRUCTION

Harvey J. Lounsbury, Glen Ellyn, Ill., assignor to
 W. H. Miner, Inc., Chicago, Ill., a corporation
 of Delaware

Application July 9, 1941, Serial No. 401,553

2 Claims. (Cl. 105—200)

This invention relates to improvements in car construction.

One object of the invention is to provide a locking center pin for body and truck bolsters of railway cars provided with center pin receiving openings and annular retaining shoulders adjacent the openings respectively, the center pin proper being composed of three outer sections and a central filler element adapted to be applied either from above the body bolster or from underneath the truck bolster.

A further object of the invention is to provide a center pin of the character set forth in the preceding paragraph, wherein simple, efficient, and reliable means are employed for locking together the filler element and the outer sections of the pin to prevent removal of the latter from the bolsters.

Other objects of the invention will more clearly appear from the description and claims herein-after following.

In the drawings forming a part of this specification Figure 1 is a bottom plan view of a portion of the truck bolster of a railway car, illustrating my improvements in connection therewith. Figure 2 is a vertical sectional view through the body and truck bolsters of the car, corresponding substantially to the line 2—2 of Figure 1. Figure 3 is a horizontal, transverse sectional view of the center pin only, corresponding substantially to the line 3—3 of Figure 2. Figure 4 is a top plan view of the pin as shown in Figure 2. Figure 5 is a detailed perspective view of the filler element of the center pin. Figure 6 is a detailed perspective view of one of the outer sections of my improved center pin. Figure 7 is a view similar to Figure 2 illustrating the pin in position applied from above the body bolster. Figure 8 is a top plan view of Figure 7.

In said drawings, 10 indicates the body bolster of the car and 11 the truck bolster. The body bolster is of the cast type and has diaphragm sections 12—12, top and bottom walls 13—14, and a center section 15 to accommodate the pin. The section 15 is of cylindrical, tubular form, as shown, and has an internal, inwardly projecting, horizontal, annular flange 16 between the top and bottom ends thereof, thereby providing a pocket 17 at the top of the bolster adapted to accommodate the head at the upper end of the pin. Below the flange 16 near the lower end of the section 15 is provided a second interior, inwardly projecting flange 18 similar to said flange 16, thereby providing a relatively shallow pocket 19 at the bottom of the section 15.

As will be evident, the annular flanges 16 and 18 provide vertically aligned circular openings. These openings are of such a size as to accommodate the shank portion of the center pin.

5 The truck bolster 11, which is also preferably a casting, has top and bottom walls 20 and 21 connected by transverse, vertically disposed walls 22—22. The bolster 11 is also provided with reinforcing webs 23 connecting the walls 20 and 22. The spaced walls 22 define a pocket 24 therebetween which serves to accommodate the bottom head of the center pin. The top wall 20 of the bolster 11 is provided with a center pin receiving opening 25 of the same size as, and in vertical alignment with, the openings at the flanges 16 and 18 of the bolster 10. A bearing plate 26 and a filler block 27 are secured to the top of the bolster 11 in a well known manner, not illustrated, the filler block being interposed between the plate 26 and the top surface of the upper wall of the bolster and having an opening therethrough registering with the opening 25. The plate 26 is also provided with an opening 28 defined by an upstanding, hollow, annular flange 29 which projects into and is accommodated within the pocket 19 at the bottom end of the section 15 of the bolster 10. The opening 28 is in axial alignment with the opening defined by the flanges 16 and 18 of the body bolster, the opening of the block 27, and the opening 25 of the truck bolster. All of these openings are of the same diameter and of slightly greater size than the diameter of the pin.

20 My improved locking center pin, as shown, comprises broadly three outer members A—A—A and a filler element B having three radial wings fitting respectively between said outer members.

25 The outer members A—A—A, which are three in number, are arranged symmetrically about the vertical central axis of the pin. Each outer member is of sector-shaped cross section having laterally diverging inner side faces 30—30 and a transversely curved outer face 31. At the top and bottom ends, each member is provided with relatively heavy, horizontally disposed, arcuate flanges 32—32 which project laterally outwardly from the body of the member and form top and bottom head portions. The three sections A—A—A of the pin are all alike and when assembled define a sectional cylindrical pin having a shank of circular cross section and head members at opposite ends. The top flange 32 of each outer member is eccentric to the cylindrical outer face 31, which defines a portion of the outer surface of the shank of the pin, each flange 32 being 30 of such a size that it will readily pass through

the pin receiving openings of the body and truck bolsters when the filler element B is not present and the remaining two outer members are disposed within the pin receiving openings with their respective flanges overhanging the shoulders formed at the outer ends of the pin receiving openings of said bolsters. The arcuate flanges at the lower ends of the section A are preferably concentric to the cylindrical shank of the pin.

The filler element B comprises three plate-like wings 33—33—33 radial to the central longitudinal axis of the pin. The wings 33—33—33 are spaced equal distances apart and merge at the center of the pin to form a central shank portion 34. These platelike sections are of such a thickness that they fill the spaces between the outer members A—A—A to form with said outer members a complete pin of true cylindrical form. At the lower end, each wing 33 is laterally, outwardly enlarged to provide a retaining lug or head 35. The filler element B is of such a size that the vertical outer edges of the wings 33—33—33 thereof are flush with the outer sides of the members A—A—A when the parts of the pin are in completely assembled condition.

At the lower end below the lugs 35 thereof the filler element B is provided with a relatively narrow neck portion 36 having at its outer end a flat, disc like head 37 which is horizontally disposed. This disc like head 37 facilitates removal of the filler element when the same has been applied from above the body bolster, as hereinafter explained:

Each section A of the pin has a depending lug 38 at the bottom end projecting from the bottom head 32 thereof. The lug 38 is substantially radial and has its side face flush with one of the side faces of the section A. Each lug 38 is provided with an opening 39 extending therethrough which is laterally elongated and adapted to receive a locking bolt 40. The perforated lug 38 of each section A also serves as an eye to be engaged by a hook or similar tool by which the section may be withdrawn from the center pin openings of the bolsters.

As shown in Figures 1 and 2 of the drawings the center pin is in position as applied from underneath the truck bolster. When thus applied the pin comprising the outer members A—A—A and the filler element B, substantially fills the pin receiving openings of the two bolsters and the flanges 32—32 at the top and bottom ends of the outer members form enlarged top and bottom head portions respectively, which hold the pin against removal from the bolsters. The filler element B is held against removal from between the sections A—A—A in a downward direction by the locking bolts 40—40 which extend through the openings 39 in the lugs 38 of the sections A and have their heads underlying the lugs 35 of the filler element B. As will be seen upon referring to Figure 2, the lugs 38 are accommodated in the space between the head 37 and the lugs 35 of the filler element B, and considerable clearance is provided between said head 37 and the lower extremities of these lugs.

In applying the center pin from beneath the truck bolster, the outer sections A—A—A and the filler element B are disposed in the positions shown in Figures 5 and 6, that is with the sections A turned so that the ends thereof having the lugs 38 are at the bottom, and the filler element B turned so that the end thereof which

is provided with the lugs 35—35—35 and the head 37 is disposed at the bottom.

The three members A—A—A are first inserted in the pin receiving openings of said bolsters by passing them one at a time and in succession into said openings, each member after having been inserted being displaced radially outwardly to bring the heads thereof in shouldered engagement with the bolsters before the next member is inserted, thus leaving sufficient space for passage of the head of the latter. With the two outer members thus inserted and radially displaced and in side contact with each other, the space left, or clearance provided in said pin receiving openings, is just sufficient to permit passage therethrough of the head of the third or remaining member. After the three outer members have been inserted and each member displaced radially outwardly into shouldered engagement with the bolsters, the filler element B is applied by inserting the same into the pin receiving openings of the bolsters from beneath the truck bolster, and engaging the wings 33—33—33 of said element between said outer members A—A—A.

The bolts 40 are then applied, being inserted through the openings of the lugs 38 of the section A so that the heads of said bolts underlie the lugs 35—35—35 of the element B. As will be evident the lugs 35 of the element B rest upon the heads of the bolts 40 when the latter are in position, thus preventing removal of the filler element from between the outer sections A—A—A.

In removing the pin a reverse procedure is followed, the locking bolts 40 being first removed to free the filler element B, the latter is removed by withdrawing the same from between the three outer members A—A—A in downward direction thereby permitting collapse of said members. In withdrawing the filler element the head 37 is utilized as a grip. The same may be removed by the attendant grasping the head 37 with his fingers or engaging the same by a hook or similar removing tool.

After the sections A—A—A have been placed in condition to collapse through removal of the filler element, the same are withdrawn in succession, each member in each instance being first displaced radially inwardly to a sufficient extent to clear the flange 32 at the upper end thereof from shouldered engagement with the body bolster. In withdrawing the sections A—A—A a hook or similar tool may be employed, the same being engaged within the perforated lugs 38 of said sections.

As hereinbefore stated my improved center pin may also be applied from above the body bolster and Figures 7 and 8 show such an application of the pin. When the pin is applied from above the body bolster the sections A—A—A and the filler element B are reversed from the positions shown in Figures 5 and 6, that is they are so arranged that the ends of the sections A provided with the lugs 38 and the end of the filler element B having the head 37 are disposed at the top.

In this applied position the lugs 35—35—35 of the element B of the assembled pin overhang and rest upon the shoulder provided by the flange 16 of the section 15 of the body bolster, thus preventing removal of the filler element in downward direction. As will be evident, and as shown in Figure 7, when the pin is thus applied from

above the body bolster the locking bolts 40 are not required and may be entirely omitted.

In applying the pin from above the truck bolster the procedure is the same as that hereinbefore described with the exception that all of the sections A—A—A and the filler element B are applied from above instead of from below.

In removal of the pin from above the truck bolster the head 37 of the filler element B and the lugs 38 of the sections A—A—A provide convenient grips for manipulating the parts. The order of removal of the parts of the pin is the same as hereinbefore stated in connection with the removal of the pin from underneath the truck bolster.

I have herein shown and described what I now consider the preferred manner of carrying out my invention, but the same is merely illustrative and I contemplate all changes and modifications that come within the scope of the claims appended hereto.

I claim:

1. In car construction, the combination with body and truck bolsters having alined center pin receiving openings, each of said bolsters being provided with an annular shoulder adjacent the outer end of the opening thereof; of a sectional center pin including three similar outer sections shouldered at opposite ends and adapted to be entered through said openings, and a filler element comprising a central member and three radially extending wings, said wings being engaged between said outer sections to hold the latter spread apart with the shoulders thereof in overlapped relation with the annular shoulders of the bolsters, said outer sections having perforated protruding lugs at one set of ends thereof, the axis of perforation of each of said lugs being to one side of the longitudinal center line of the pin, said filler element having laterally extending lugs at one end thereof adjacent said

perforated lugs of the outer sections spaced inwardly from the latter, and a disclike head projecting from said end of the filler element; and retaining elements extending through the perforations of said lugs and into underlying relation with said laterally extending lugs of said filler element to be engaged by said last named lugs and support said filler element against removal.

10 2. In a center pin for connecting the body and truck bolsters of a railway car having alined center pin receiving openings, each of said bolsters being provided with an annular shoulder adjacent the outer end of the opening thereof, said pin being substantially cylindrical and including three main outer members of sector shaped cross section having heads at opposite ends adapted to have shouldered engagement with the annular shoulders of the bolsters, and a spreader element including a central filler section and three radially projecting spacing wings, each wing being engaged between the sides of two adjacent outer members, each wing having an outwardly projecting lug at one end of said spreader element, each of said outer members having a depending eye member on the corresponding end thereof alongside the corresponding lug of the spreader element with the opening of the eye outwardly of said lug, with the axis of said opening offset to one side of the longitudinal central axis of said pin, a retaining bolt engaged through the eye of at least one of said outer members with the head of said bolt in line with and supporting the adjacent lug of the spreader element to hold said spreader element against removal in lengthwise direction, and a disclike head on the same end of said spreading element which is provided with the lug, said head projecting outwardly beyond said lug in a direction lengthwise of the pin.

HARVEY J. LOUNSBURY.
